REVERSIBLE WINDOW SHADE AND SECURING MEANS

Filed June 17, 1929

UNITED STATES PATENT OFFICE

MARY E. MURPHY, OF DALLAS, TEXAS

REVERSIBLE WINDOW SHADE AND SECURING MEANS

Application filed June 17, 1929. Serial No. 371,471.

This invention relates to new and useful improvements in window shades and has particular reference to a novel means of securing window shades to the conventional rollers 5 to prevent their disengagement from the latter under strain.

Another object of the invention resides in the provision of a novel means of attaching shades to rollers so that the shades may 10 be reversed and consequently renewed at their lower ends, which often become soiled and torn.

Still another object of the invention is manifest in the provision of a means, as 15 described, capable of saving considerable expense, since the upper portion of the shade may be changed to the bottom with little effort, resulting in longer life for shades under normal conditions.

20 A further object of the invention resides in the provision of an improved shade as described, especially adapted to use in schools where children often handle the shades and for other public places where many people 25 are likely to be careless in drawing them down, causing the shade to unwind from the roller and become detached therefrom.

Having thus set forth its novel objects and salient features of construction, a more 30 detailed description of the invention follows, taken in connection with the appended drawings in which:—

Figure 1 is a perspective view showing the invention as applied to both the upper and 35 lower ends of a shade.

Figure 2 is a cross-section of a roller showing the way in which the shade is attached.

Figure 3 is a modification of the securing means showing a clamp having teeth.

40 Figure 4 shows the preferred means of securing the shade to the roller.

Figure 5 is a modification of the securing means shown in Figure 4.

Figure 6 is a plan view of securing means 45 shown in Figure 5.

Figure 7 is a perspective view of the clamp shown in Figure 3, and

50 Figure 8 is a fragmentary elevational view of the invention as applied to a roller, showing the preferred style of stitching the shade

and a type of wire staples used for securing the shade to the roller.

The ordinary method of securing window shades to the rollers with tacks or clips is unsatisfactory, due to the fact that when 55 the shade is completely unwound from the roller, a little strain might tear it loose, resulting in not only damaging the end connected to the roller, but endangering the shade as a whole, since a wrinkle or a crease 60 in material such as used for window shades will break the texture and allow the light to show through.

Under the ordinary methods, it is not practical to reverse the ends of the window shades 65 for the reason that only one end of the latter is hemmed to form an enclosure for a stick, which is universally used in window shades to maintain rigidity at the bottom. The method herein described provides a hem of 70 like dimensions on either end of the shade in which either the roller, at the top, or the stick at the bottom, may be inserted.

Proceeding more in detail, reference is again made to the drawings and primarily 75 to the character 1 representing the shade, either end of which is hemmed to define a tube-like enclosure 2. Through the topmost of these enclosures 2, a conventional shade roller 3 is inserted, while a stick 4, is inserted 80 through the lowermost enclosure, as shown in Figure 1.

Particular reference is made to Figure 2 showing the relationship of the roller 3 to the enclosure 2 and one means of securing the 85 folded edge *a* of the shade to the shade surface. This may be accomplished by stitching, as shown in Figures 1 and 8 at *b*, and in Figure 3 at *c* or by gluing the surfaces together 90 as shown in Figure 2.

As the enclosures 2 must be of such dimensions as to allow the roller 3 to be freely inserted therein, a means must be provided to prevent the shade from slipping on the roller. This may be accomplished by the use of small 95 wire staples 5, inserted into the roller but a preferred means of securing the shade to the roller is a clasp as exemplified in Figure 4, which comprises a small strip of metal 6 of such shape as to be applied to the roller by 100

tacks or the like, at one end, the opposite end of which is sharpened to define a point 7 which can be pressed into the roller 3 through the shade 1 to prevent the latter from turning on the roller 3.

It is not intended, however, to limit the clasp 6 to the structure shown in Figure 4 and for that reason a modified type of clasp is shown in Figures 5 and 6. The metal caps 10 8 of the roller are constructed to define a tongue 9 having a point 10, similar to that of the clasp 6 which may be pressed into the roller as shown in Figure 5.

In order to prevent an excess of unsightly perforations in the enclosure 2, through which the roller 3 operates, it is desirable to place the clasps 6 and 9 immediately upon top of the roller when the shade is placed thereon. This will place the small perforations made by the 20 points 7 and 10 of the clasps at the bottom of the stick 4 in the lower enclosure 2 when the shade has been reversed.

A further modification of a means for securing the shade 1 to the roller 3, is shown 25 in Figures 3 and 7. A springlike clamp 11 is provided, having triangular shaped portions cut from the ends thereof and turned inwardly to define teeth 12 which may be pressed into the roller 3 to hold the shade secure to the latter.

When it is desired to reverse the shade, the clasp 6 or 9 can be lifted in the manner shown in Figures 4 and 8 and the shade slipped from the roller 3. The opposite end may be 35 slipped on the roller 3 and the clasps 6 and 9 may be pressed down again.

Obviously, considerable modifications may be made in the construction shown and such modifications as are considered within the 40 scope and meaning of the appended claims without departing from the spirit and intent of the appended claims.

What is claimed is:

1. In a reversible window shade, the combination of a sheet of fabric having hems of equal size at either end, and a securing means including a clamp comprised of semi-cylindrical rings joined together at their opposite ends by integral strips disposed in parallel 50 relationship, the said rings having substantially triangular projections struck inwardly therefrom at a point adjacent the ends thereof.

2. In a reversible window shade, the combination of a sheet of fabric having hems of equal size at either end, and securing means including substantially cylindrical clamps arranged to embrace the mounting for said fabric and having a portion cut out therefrom 60 to define a substantially skeleton structure and having substantially triangular projections struck inwardly adjacent its ends to be received in said mounting.

In testimony whereof I affix my signature.
65 MARY E. MURPHY.
